(57) **CLAIM**

The ornamental design for a cradle for hand held electrical device, as shown and described.

DESCRIPTION

FIG. 1 is a rear perspective view of the cradle for hand held electrical device showing my new design;

FIG. 2 is a rear plan view thereof;

FIG. 3 is front plan view of the hand held electrical device showing my new design;

FIG. 4 is a right side elevational view thereof;

FIG. 5 is a left side elevational view thereof;

FIG. 6 is the top end plan view thereof; and,

FIG. 7 is the bottom end plan view thereof.

The broken lines represent portions of the structure that forms no part of the claim.
